(57) **CLAIM**

The ornamental design for an armchair, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of an armchair, showing my new design in an upright position;

FIG. 2 is a front view thereof;

FIG. 3 is a back view thereof;

FIG. 4 is a side view thereof;

FIG. 5 is a side view thereof opposite that of FIG. 4;

FIG. 6 is a top view thereof;

FIG. 7 is a bottom view thereof;

FIG. 8 is a lower front perspective view thereof;

FIG. 9 is a rear perspective view thereof;

FIG. 10 is a front perspective view of the armchair of FIG. 1, shown in a fully reclined position;

FIG. 11 is a front view thereof;

FIG. 12 is a back view thereof;

FIG. 13 is a side view thereof;

FIG. 14 is a side view opposite that of FIG. 13, showing the armchair in a partially reclined position;

FIG. 15 is a top view thereof;

FIG. 16 is a bottom view thereof;

FIG. 17 is a lower front perspective view of the armchair, shown in a fully reclined position; and,

FIG. 18 is a rear perspective view thereof.
